TERRAZZO STRIP

Edward S. Cornell, Jr., Larchmont, N. Y.

Application December 31, 1931, Serial No. 584,020

4 Claims. (Cl. 94—17)

My present invention relates to patterns or guide strips for plastic work and more particularly to an improved pattern or guide strip for surface coverings such as terrazzo flooring and the like.

An object of my invention is to provide an improved device which may be easily and accurately placed in position and which when in position will be prevented from moving laterally or longitudinally of the material in which the same is placed.

An object of my invention is a pattern or guide strip of this character in which the upper and lower edges are continuous or unbroken and in which is formed a plurality of openings along the length of the strip, such openings being of a character to enable a bonding action to take place between materials of the plurality of layers in which the same is placed during the laying of a terrazzo floor.

An object of my invention is a means for preventing too great depression of the strip into the under or screed layer of a terrazzo floor and which, when in position defines a parting line 25 between the screed and terrazzo layers.

An object of my invention is an improved pattern or guide strip of this character in which a plurality of ears extend outwardly on each side of the body, said ears being formed out of the material of the body and so positioned as to have the material of the body below the horizontal level of such ears intact or unbroken.

Other objects and novel features of the construction and arrangement of parts comprising my improved device will appear as the description of the invention progresses.

In the accompanying drawings:

Fig. 1 is a perspective view of the preferred form of my invention;

40 Fig. 2 is a sectional plan view on the line 2—2 of Fig. 1;

Fig. 3 is a side elevation of a portion of a strip showing the material of the laterally extending ears blanked out but before bending the same into final shape and position;

Fig. 4 is a sectional end elevation on the line 4-4 of Fig. 1, showing the same in position in a section of terrazzo flooring;

50 Fig. 5 is a perspective view of a modified form of my device;

Fig. 6 is a side elevation of a portion of a strip and showing the material to ultimately form the lugs blanked out but in position in the strip.

Fig. 7 is a sectional plan view on the line 7—7 of Fig. 5;

Fig. 8 is a perspective view of a still further modification of my invention; and

Fig. 9 is a plan view of Fig. 8 partly in section, the section portion being shown on the line 9-9 of Fig. 8.

Referring to the drawings and particularly to Figs. 1 to 4, inclusive, 10 designates a strip of material preferably of hard drawn brass and of appropriate length, width and thickness, having extending outwardly therefrom and on each side thereof, ears 11 and 12, it being understood that although but one each of the ears 11 and 12 are shown, that a plurality of such ears are provided, being arranged in spaced relationship along the length of the strip 10. Referring specifically to Fig. 3, there is formed lengthwise of the strip 10 a slot 13, this slot being formed by a punch or any other suitable manner. Blanked out from the material of the strip 10 and along the lines 14, 15, 16, 17 and 18 is a blank which obviously forms at its upper end the ears 11 and 12. It will be noted that this blank is not severed from the material of the strip 10 being integrally united therewith at the dotted line 20. The blank defined by the lines 19 above referred to is then bent along the dotted line 19, the upper portion of such blank being moved outwardly, as viewed in Fig. 3, after which the blank is bent along the dotted line 20 forcing the portion 12 of such blank through the slot 13 and into the position shown in Fig. 2. It will be noted that the portion of the blank defined by the lines 17, 18, 19 and 20 now lies perpendicular to the plane in which lies the strip 10 and this portion is designated by the reference numeral 21.

Referring specifically to Fig. 4, showing my improved strip in place in a section of terrazzo flooring wherein 22 designates the usual concrete aggregate base and 23 the screed coat of cement laid thereon, and 24 the top or terrazzo layer, the strip 10 is forced through the screed layer before such layer has set and the downward movement of such strip 10 will continue until the ears 11 and 12 move into engagement with the top surface of such screed layer. The downward movement is therefore arrested and the ears 11 and 12 form a shelf which defines the upper layer of the screed coat 23. The terrazzo layer 24 is now laid in position on top of the screed layer 23 and it is obvious that the various sections of the terrazzo layer as the sections 25 and 26 are bonded together by the passage of the materials constituting such sections 25 and 26 through the orifice formed in the strip 10.

10 by the removal therefrom of the material now forming the ears 11 and 12. Also, it will be obvious that the sections of the screed layer 23 adjacent each other are also bonded together 5 by the said passage of material therefrom passing through the perforation in the strip 10 formed by the bending of the member 21 outward therefrom at right angles thereto.

15 It will be noted that the bonding between the various sections of the terrazzo layer 24 and the screed layer 23 takes place by natural flow of the materials thereof through the perforations formed by the removal of the ears 11 and 12, as the material of the strip 10 immediately thereunder is imperforate and it will be obvious that there is no tamping section on the material of the screed layer 23 by the ears 11 and 12 to tamp such material through any perforation in the strip to cause a bonding of the section of the material thereof. This prevention of tamping of the material through a perforation by the ear 11 is accentuated by the presence of the member 21 extending at right angles to the strip 10 and adjacent the edge of the perforation formed by blanking out the ears 11 and 12.

20 Referring now to Figs. 5, 6 and 7, showing a modification of my invention, the strip 10 is provided with a slot 27 extending longitudinally of the strip 10 and intermediate the upper and lower edges thereof. A section of the material of the strip 10 is then blanked out along full lines 28, 29, 30 and 31 but such blank is held integral with the strip 10 along the material defined by the dotted line 31. The blank as struck out is then bent along the dotted line 31, the portion 32 of the blank extending outward from the strip 10 as indicated in Fig. 7. The portion 33 of the blank is then bent along the dotted line 34 and such portion 33 defines the ears 35 and 36 respectively. The portion 37 of the blank is then bent along the dotted line 38a inwardly toward the strip as easily shown in Fig. 7, thus forcing the portion 33 of the blank into the slot 27 so as to position the ears 35 and 36 on either side of the strip 10 as clearly shown in Fig. 7. The portion 38 of the blank is then bent with respect to the portion 37 of such blank along the dotted line 39 so as to lie at right angles to the strip 10 and forms a means for preventing longitudinal movement of the strip 10 in the screed layer 23. The strip 10 as shown in Figs. 5, 6 and 7 is assembled in the terrazzo flooring in identically the same manner as described with regard to the strip 10 in Figs. 1, 2, 3 and 4 and it will be noted that the member 38 not only prevents longitudinal movement of the strip 10 in the screed layer but also acts to prevent any tamping action on the part of the ear 35 to cause a forced flow of the material of the screed layer 23 through the perforation in the strip 10 formed by the removal of the blank above described. Also, it will be noted that the prevention of longitudinal movement of the strip 10 is enhanced by the construction and arrangement of the portions 32 and 37 of the blank referred to. Further no tamping action on the part of the ear 35 can take place on the material of the screed layer 23 as the material of the strip 10 below such ear 38 is imperforate.

70 It is to be understood that the modification of my invention as shown in Figs. 5, 6 and 7 comprehends the utilization of a plurality of pairs of ears 35 and 36 spaced along the length of the strip 10 at any appropriate distances as is also

the case with respect to the embodiment of my invention shown in Figs. 1, 2, 3 and 4.

5 Referring now to Figs. 8 and 9, there is shown the strip 10 provided with perforations 39 and 40 spaced along the length of the strip 10, the material blanked out from the strip 10 to form such perforations 39 and 40 being held integral with the strip 10 and one of such pieces of material being bent outwardly from the strip 10 to form a member 41 or 42 extending at right angles to the strip 10 and this member 41 or 42 is then bent over to form an ear 43 or 44 which ears 43 and 44 lie at right angles to but extend longitudinally of the strip 10. It will be noted that the members 41 and 43 extend laterally outward from the strip 10 on one face thereof and that the members 42, 44 extend laterally outward from the opposite face of the strip 10. Also, each alternate pair of members 41, 43, and 42, 44, extend laterally outward from alternate sides of the strip 10, as clearly shown in Figs. 8 and 9.

15 From the above, it will appear that the various types of my terrazzo strip comprise a thin strip of metal adapted to be positioned vertically in a flooring such as a screed layer and a superimposed terrazzo layer, such strip being provided with a plurality of sets of ear formations, each ear formation having a vertically extending portion and a horizontally extending portion, the body of the strip having a perforation adjacent the ear formation, such ear formation being integrally connected with the body of the strip at a vertical edge of such perforation, such ear formations projecting in direction relative to the body of the strip away from its associated perforation.

25 While I have necessarily shown and described the preferred embodiments of my invention somewhat in detail, it is to be understood that I may vary the size, shape and arrangement of parts comprising my improved device within relatively wide limits without departing from the spirit of the invention.

30 I claim:

1. A terrazzo strip comprising a thin strip of material adapted to be positioned vertically in a flooring such as a screed layer and a superimposed terrazzo layer, said strip being provided with a plurality of sets of ear formations, each ear formation comprising a vertically extending portion and a horizontally extending portion, the body of the strip having a perforation adjacent the ear formation, said vertically extending portion being integral with the body of the strip at an edge of such perforation, said horizontally extending ear portion projecting in direction away from its associated perforation.

45 2. A terrazzo strip comprising a thin strip of material adapted to be positioned vertically in a flooring comprising a screed layer and a superimposed terrazzo layer, said strip being provided with a plurality of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

50 3. A terrazzo strip comprising a thin strip of material adapted to be positioned vertically in a flooring such as a screed layer and a superimposed terrazzo layer, said strip being provided with a plurality of sets of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

55 4. A terrazzo strip comprising a thin strip of material adapted to be positioned vertically in a flooring such as a screed layer and a superimposed terrazzo layer, said strip being provided with a plurality of sets of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

60 5. A terrazzo strip comprising a thin strip of material adapted to be positioned vertically in a flooring such as a screed layer and a superimposed terrazzo layer, said strip being provided with a plurality of sets of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

65 6. A terrazzo strip comprising a thin strip of material adapted to be positioned vertically in a flooring such as a screed layer and a superimposed terrazzo layer, said strip being provided with a plurality of sets of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

70 7. A terrazzo strip comprising a thin strip of material adapted to be positioned vertically in a flooring such as a screed layer and a superimposed terrazzo layer, said strip being provided with a plurality of sets of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

75 8. A terrazzo strip comprising a thin strip of material adapted to be positioned vertically in a flooring such as a screed layer and a superimposed terrazzo layer, said strip being provided with a plurality of sets of ear formations, each ear formation having a vertically extending portion and a horizontally extending portion, the body of the strip having a perforation adjacent the ear formation, the perforation having a vertical edge portion, the vertically extending portion of the ear formation being connected to the strip at the vertical edge portion of the perforation, the strip further having a slot adjacent the perforation, the horizontally extending portion of the ear formation projecting through the slot.

- posed terrazzo layer, said strip being provided with a plurality of sets of ear formations, each ear formation having a vertically extending portion and a horizontally extending portion, the body of the strip having a perforation adjacent the ear formation, the perforation having a vertical edge, said vertically extending ear portion being integral with the body of the strip at said vertical edge of such perforation and extending substantially at right angles to the body of the strip, said horizontally extending ear portion being integral with its associated vertically extending ear portion and projecting in direction away from its associated perforation.
- 5 10 15
4. A terrazzo strip comprising a thin strip of material adapted to be positioned vertically in a flooring comprising a screed layer and a superimposed terrazzo layer, said strip being provided with a plurality of ear formations, each ear formation having a vertically extending portion and a horizontally extending portion, the body of the strip having a perforation adjacent the ear formation, the perforation having a vertical edge portion, the vertically extending portion of the ear formation being integrally connected to the strip at the vertical edge portion of the perforation, the strip further having a slot adjacent the perforation, the horizontally extending portion of the ear formation projecting through the slot.

EDWARD S. CORNELL, JR. 15
